MOTOR FUEL MANUFACTURE

Rodney V. Shankland, Chicago, Ill., assignor to
Standard Oil Company, Chicago, Ill., a corpora-
tion of Indiana

Application December 30, 1938, Serial No. 248,626

5 Claims. (Cl. 196—10)

This invention relates to motor fuel manufacture and more particularly to processes for the manufacture of motor fuel constituents having high antiknock properties. Still more specifically it relates to the production of such motor fuel constituents of the branched-chain paraffin type from readily available mixtures of normally gaseous hydrocarbons.

In the operation of many refineries large quantities of hydrocarbon gases having three to four carbon atoms per molecule and containing a considerable proportion of unsaturated constituents are produced. "Plant butane" for example is a fraction composed of the butanes and butylenes which is a suitable starting material for practicing my invention. Another such material is a somewhat wider cut containing propane and propylene as well as the butanes and butylenes. However, it is not essential that the feed stocks used in carrying out my invention contain unsaturated hydrocarbons, since in certain forms thereof saturated fractions having three to four carbon atoms per molecule, such as those obtained from natural gas, can be used to advantage.

I have found that such hydrocarbon fractions can be most efficiently utilized by converting them to branched-chain paraffin hydrocarbons boiling in the motor fuel range by a combination of alkylation, fractionation and isomerization whereby the various constituents are handled so that the largest yield of branched-chain paraffin hydrocarbons is obtained therefrom. While the exact nature of the final product depends to a considerable extent upon the character of the feed stock, it can be said that in general it consists predominantly of branched-chain paraffins having seven to eight carbon atoms per molecule, and for this reason has a very high antiknock value and is very stable against the formation of gum and other deterioration products. Furthermore my product has a higher heat content per unit of weight than other types of hydrocarbon fuels and is therefore particularly suited for use as a major constituent of aviation gasoline.

It is an object of my invention to provide an efficient method for the production of valuable motor fuel constituents which are rich in branched-chain paraffin hydrocarbons from normally gaseous hydrocarbon mixtures. Another object is to provide a process for manufacturing normally liquid hydrocarbon mixtures having good antiknock and stability characteristics from gases containing substantial proportions of con-

stituents having four carbon atoms per molecule. A further object is to provide a novel unitary process for the production of liquid hydrocarbons suitable for use as aviation gasoline constituents from readily available mixtures of normally gaseous hydrocarbons. Further objects and advantages of my invention will be apparent from the following detailed description thereof read in conjunction with the drawing, which shows schematically one form of apparatus suitable for carrying out my invention in several of its modifications.

In one of its broadest aspects my invention comprises the fractionation of a substantially saturated normally gaseous fraction containing a considerable proportion of the butanes and not more than a relatively small amount of hydrocarbons having less than three carbon atoms per molecule to form a fraction rich in isobutane and a fraction rich in normal butane, alkylating the isobutane with at least one olefin having three to four carbon atoms per molecule in the presence of an alkylation catalyst, isomerizing the normal butane to form isobutane, utilizing the isobutane thus formed in the alkylation step, and passing the off-gas from the alkylation step into the fractionation step. If propane is supplied to the fractionation step as well as the butanes, a fraction rich in propane can also be obtained, and this can be dehydrogenated to propylene and the latter utilized as all or a part of the olefin supplied to the alkylation step. Optionally a portion of the normal butane fraction can be similarly dehydrogenated and the resulting butylene utilized for the alkylation of isobutane. My invention also includes many other features which will be brought out as the description thereof proceeds.

While my invention has a large number of applications, several examples will suffice to make it easily understood in its various modifications, and the first of these will bring out my improved method of producing a fraction containing a large proportion of branched-chain heptanes and octanes from a normally gaseous mixture of the paraffin and olefin hydrocarbons containing three and four carbon atoms per molecule. A typical feed stock of this kind for example is a plant propane-butane cut obtained from the fractionation of the products of the thermal cracking of heavy oils to form gasoline, which contains about 25% to 50% of olefins and about 10% to 25% of isobutane, the remainder being largely propane and normal butane. Referring now to the drawing, the normally gaseous

feed stock is introduced into the system by means of line 1 and pump 2, and passes through valve 3 into line 4, in which it is admixed with a stream of hydrocarbons rich in isobutane from a source which will be described below supplied by pump 5 and line 6. This stream can if desired also contain some propylene and/or butylenes, but in any event is supplied in such amount that the ratio of isobutane to olefin molecules in line 4 is not less than about 2 to 1. The entire mixture then passes into alkylation chamber 7 in which the propylene and butylenes are caused to combine with the isobutane in the presence of a catalyst to form branched-chain heptanes and octanes.

The alkylation step of my process can be carried out in a number of ways, for example, by relatively low-temperature low-pressure reaction in the presence of concentrated sulfuric acid or the like, or by relatively high-temperature high-pressure reaction over a solid alkylation catalyst such as sodium or lithium chloro-aluminate on an inert support such as pumice. If the latter type of alkylation is used in practicing my invention, pressures of the order of 500-1500 pounds per square inch and temperatures of 150°-500° F. are suitable, but I prefer the former type of alkylation and will describe my invention in connection therewith. Briefly, low-temperature low-pressure alkylation of isobutane with olefins having three to four carbon atoms per molecule is carried out by intimately contacting them in the liquid phase with concentrated sulfuric acid having an H₂SO₄ content of 90-100% and preferably 95-98% at a temperature of about 0° F. to 100° F. and a pressure between atmospheric and about 50 pounds per square inch. The time of contact may range from about 10 minutes to about 180 minutes and is preferably from about 60 minutes to about 90 minutes.

The sulfuric acid catalyst is supplied to the lower portion of alkylation chamber 7 by means of pump 8, valve 9 and line 10. Chamber 7 is so arranged that the reacting constituents and the sulfuric acid are kept in intimate association under the desired conditions during the required reaction time, and is shown as a vertical vessel equipped with stirring mechanism 11, although other types may, of course, be used. Cooling means must also be provided, but these are obvious to those skilled in the art and are omitted from the drawing for the sake of simplicity. The principal products of the reaction are, as stated above, branched-chain heptanes and octanes, but certain heavier branched-chain hydrocarbons and polymers are also formed to some extent. The entire reaction mixture is withdrawn from alkylation chamber 7 by means of line 12 and introduced into separator 13 in which the acid is allowed to separate from the liquid hydrocarbons. The separated acid has lost very little of its activity and consequently is recycled by means of line 14, pump 15, line 16 and line 10. Eventually, however, the acid will become sufficiently diluted or contaminated with by-products so that it is withdrawn from the system through valve 17 and line 18, but this spent acid can, of course, be regenerated by well-known means (not shown) and reused.

The upper hydrocarbon layer is withdrawn from separator 13 through line 19 and introduced into the lower portion of scrubber 20, in which it is washed with a dilute alkali solution supplied by line 21 and withdrawn through line 22 in order to remove traces of acid therefrom.

The washed product is removed from scrubber 20 through line 23 and forced by pump 24 through heater 25 into fractionating tower 26, which is of the conventional type and operated in a well-known manner so as to produce an overhead fraction withdrawn through line 27 consisting predominantly of butanes and lighter gases including unreacted isobutane, a bottom product consisting predominantly of hydrocarbons boiling above about 275° F. and having 9 or more carbon atoms per molecule withdrawn through line 28 and a sidestream containing the products of the alkylation which is withdrawn through line 29 to treatment or storage. This sidestream fraction contains a large proportion of branched-chain paraffin hydrocarbons having 7 and 8 carbon atoms per molecule and is eminently suited for use in airplane fuels.

The bottom product withdrawn from fractionating tower 26 through line 28 is preferably removed from the system through valve 30 and line 31, but if desired any portion of it can be recycled through valve 32, line 33, pump 5 and line 6 to line 4 for reintroduction into the alkylation step, in which some of the heavy constituents are broken into lighter materials which enter into the reaction to form further quantities of the desired hydrocarbons.

The overhead fraction in line 27 is a substantially saturated mixture consisting predominantly of normal butane, isobutane and propane, although ethane, ethylene and lighter gases will be present if they were contained in the feed stock. This fraction is passed through cooler 34, line 35, pump 36 and line 37 into a fractionating zone, which is shown as a second fractionating tower 38 so constructed and operated as to give very close fractionation into four fractions consisting essentially of normal butane, isobutane, propane, and gases lighter than propane. The normal butane fraction is obtained as a bottom product withdrawn from fractionating tower 38 through line 39, the isobutane and propane fractions are obtained as sidestreams withdrawn through lines 40 and 41 respectively, and the gases lighter than propane are eliminated from the system as overhead through valve 42 and line 43. Obviously if desired a plurality of fractionating towers can be used in place of the single tower 38 to accomplish the same purpose.

The isobutane fraction in line 40 is passed through lines 44 and 33, pump 5 and line 6 into line 4 to enrich the isobutane content of the feed stock and adjust the isobutane-olefin ratio mentioned above to the desired value.

The normal butane fraction in line 39 is charged to an isomerization step through valves 45 and 46 and line 47 by means of pump 48 and line 49. The isomerization of the normal butane fraction to increase its isobutane content is carried out in isomerization chamber 50, preferably by treatment with a catalyst of the aluminum chloride type at an elevated temperature, e. g. from about 250° F. to about 550° F. and more particularly from 350° F. to 475° F., and an elevated pressure, e. g. from about 500 to about 6000 pounds per square inch, in the presence of an activator for the catalyst and preferably in the presence of propane and free hydrogen.

The aluminum chloride type catalyst used in carrying out the isomerization step of my invention can be for example aluminum chloride or aluminum bromide in anhydrous form, and is preferably introduced into the reaction zone in the form of a slurry or solution in a light

hydrocarbon oil. In practicing my invention relatively small amounts of catalyst per unit weight of charge, e. g. less than 10%, are required and I prefer to use about 1% to 5% by weight. As activator a hydrogen halide or any compound which in the presence of the catalyst yields a hydrogen halide under the reaction conditions can be used, preferably in an amount sufficient to supply about 0.03 to 3.0 percent by weight of hydrogen halide based on the normal butane charged. Hydrogen chloride is the preferred activator, but hydrogen bromide, carbon tetrachloride or tetrabromide, or the alkyl halides such as methyl chloride or bromide, ethyl chloride or bromide, etc are also suitable.

At the relatively high temperatures and pressures specified above, namely: 250° F. to 550° F. or preferably 350° F. to 475° F. and 500 to 6000 pounds per square inch, much higher conversions per weight of catalyst are obtained in appreciably reduced reaction times than can be obtained under milder conditions. High temperature operation in the presence of catalyst and activator alone, however, causes increased degradation of the normal butane to lighter hydrocarbons, principally propane. Under exceptional circumstances a small amount of permanent gases (ethane and lighter) are obtained but this is an indication of drastic overtreatment resulting from too high a temperature, too much catalyst or too long a time of contact. The formation of propane can be substantially completely inhibited by carrying out the reaction in the presence of a substantial amount of propane, for instance 10% to 35% by weight based on the normal butane present. The amount of the latter converted per pass is preferably held below about 35% to 40%, and this limitation of the conversion can be controlled by regulation of the temperature and/or contact time in the reaction zone or by variation of the quantity of catalyst used. Methane and ethane are without effect in preventing the degradation of the feed stock to propane and lighter gases and their presence in the reaction zone is generally undesirable since they act as diluents for the reaction mixture, but minor quantities can, of course, be present.

As hereinabove stated the isomerization reaction is preferably carried out in the presence of free hydrogen. At the relatively high temperatures at which this reaction is preferably operated, hydrogen greatly retards the rate of deactivation of the catalyst, thereby allowing especially high yields of isobutane per unit of catalyst.

Referring again to the drawing, the normal butane fraction in line 49 is introduced into the lower portion of the isomerization chamber 50, which is shown as a jacketed pressure vessel equipped with a stirring device 51 so that the reaction materials are thoroughly contacted. The desired reaction temperature is maintained by passing a suitable gaseous or liquid heating agent such as steam through the jacket 52 of isomerization chamber 50 by means of inlet 53 and outlet 54.

Propane in the proper amount is introduced into line 49 through line 55, pump 56, line 57 and valve 58, and this is preferably a portion of the propane stream in line 41 which is made available by opening valve 59. In some cases, however, it will be necessary or desirable to supply propane from an external source and this can be done by opening valve 60 in line 61. Catalyst slurry and activator are likewise intro-

duced into line 49 and mixed with the feed therein by means of pumps 62 and 63, and lines 64 and 65 through valves 66 and 67, respectively. Free hydrogen is supplied to the upper portion of isomerization chamber 50 through pump 68 and line 69, and is there maintained at the desired reaction pressure, which is sufficiently high to cause the hydrogen to dissolve in the agitated reaction mixture at a rate at least as great as it is used up in the reaction. This hydrogen can be obtained from a source outside the system by means of line 70, valve 71 and line 72, but when the dehydrogenation step of my process is operated, as will be described below, it is preferably obtained therefrom through line 73, which connects with line 72. Obviously if desired a number of reaction vessels can be used in series or parallel in place of the one shown, or vessels of other types well-known in the art can be substituted therefor.

A portion of the entire reaction mixture is continuously withdrawn from the upper portion of chamber 50 through line 74 and passes through cooler 75 into separator 76. The products consist of a catalyst complex which settles out in the lower portion of separator 76, and an upper layer consisting of a mixture of isobutane, propane, unreacted normal butane, and some dissolved hydrogen. The catalyst complex is continuously withdrawn from separator 76 through line 77 and either recycled to line 64 through valve 78, pump 79 and line 80 or withdrawn from the system through valve 81 and line 82, or under some conditions a portion of the complex may be continuously withdrawn from the system and the remainder recycled. The substantially spent complex can, of course, be regenerated or the aluminum halide recovered therefrom and reintroduced into the system through pump 62.

The upper layer from separator 76 is withdrawn through line 83 and can be passed through valve 84 into line 33 to augment the isobutane supply to alkylation chamber 7, since the accompanying normal butane, propane and hydrogen are inert in the alkylation step. It is desirable, however, to avoid such dilution of the reactants in alkylation chamber 7, and the mixture in line 83 is therefore preferably introduced into fractionating tower 38 by means of valve 85, line 86, pump 87, line 88, valve 89 and line 37 for fractionation into normal butane, isobutane, propane, and ethane and lighter streams, these streams being utilized as described above. The hydrogen dissolved in the hydrocarbons in line 83 will eventually appear in the gases vented through line 43 and can be recovered therefrom and reused in the isomerization step, for example by introduction into line 70. In another method of handling the stream in line 83 the butanes are separated from the propane and lighter gases by fractionation, the propane and lighter fraction recycled to isomerization chamber 50, and the normal butane-isobutane fraction passed through valve 84 and/or valve 85 for purposes described above.

It is apparent from the above description that I have provided an efficient process for converting a mixture of paraffin and olefin hydrocarbons having predominantly three and four carbon atoms per molecule into branched-chain heptanes and octanes with efficiency and economy. The exact composition of the feed will determine to a considerable extent the rates of flow in the various parts of the system, and the exact manner of operation. In any case the isobutane and

the olefins having three and four carbon atoms per molecule are substantially completely utilized, while any excess of propane can be removed from the system through valve 90 and line 91 and any excess of normal butane can be similarly removed through valve 92 and line 93.

Under some conditions, and particularly when a feed stock relatively low in olefins is charged by means of line 1 and pump 2 to the alkylation reaction, it is desirable to increase the amount 10 of olefins available for reaction with isobutane. This can be done by opening valve 94 and allowing at least a portion of the propane fraction in line 41 to flow to a heater 95, in which it is heated to a temperature suitable for dehydrogenation. The dehydrogenation can be carried out either thermally or catalytically, but 15 preferably catalytic dehydrogenation is used, and the dehydrogenation apparatus shown for purposes of illustration therefore consists of a conventional heater 95 and a catalyst chamber 96 connected by a line 97. Catalyst chamber 96 contains a solid dehydrogenation catalyst such as chromium oxide gel, magnesium chromite, etc., and the reaction conditions are preferably 20 approximately atmospheric pressure and from about 900° F. to about 1200° F.

The dehydrogenated stream is withdrawn from the bottom of catalyst chamber 96 by means of line 98 and passes through cooler 99, and pump 100 to fractionating tower 101 which is operated under such conditions that hydrogen together with methane, if any is present, is withdrawn from the upper portion thereof through line 102 and the heavier materials which contain predominantly propylene are withdrawn as a liquefied bottom product through line 103. The uncondensed gas can be withdrawn from the system through valve 104 and line 105 or introduced to the isomerization step through valve 106, lines 25 73 and 72, pump 68 and line 69 so that it may be utilized as hereinabove described. If there is an excess of hydrogen over that required for use in the isomerization step, this excess will be withdrawn from the system through line 105. The liquid olefin fraction in line 103 passes 30 through valve 107, lines 44 and 33, pump 5 and lines 6 and 4 to alkylation chamber 7 in which it is reacted with the isobutane as previously set forth.

It is also possible to cause a portion of the normal butane fraction to be dehydrogenated to the normal butylenes by opening valve 108 in line 109. Obviously by suitable manipulation of valves 94 and 108, any desired quantity of normal butane and/or propane can be dehydrogenated and the corresponding olefins utilized in the alkylation step.

When the feed stock used is a plant butane fraction consisting predominantly of normal butane, isobutane, and the butylenes, the method of operation is exactly the same as described above, and the product consists predominantly of branched-chain octanes. Obviously, in the system shown propane will be introduced into the system through valve 60 in order to inhibit butane decomposition in isomerization chamber 60, and this will eventually find its way either directly or through the alkylation step to fractionating tower 38, from which it will be withdrawn as a sidestream through line 41 for further inhibition of butane decomposition. Generally speaking, valve 94 will be kept closed under these conditions and any olefin deficiency made up by the dehydrogenation of a portion of the normal

butane fraction in line 39 which is allowed to pass through valve 108 and line 109.

My invention is also adapted to the processing of substantially saturated normally gaseous fractions containing isobutane, normal butane and optionally propane. Such fractions are often available from the fractionation of natural gasoline or distillate recovery plant streams or as off-gas from the catalytic polymerization of refinery gases or fractions thereof. If the isobutane content is relatively high, it may be desirable to charge this fraction directly to alkylation chamber 7 by means of line 1, pump 2 and line 4, and in this case the process is operated according to one of the modifications described above, substantially all of the olefin supply to alkylation chamber 7 being provided by dehydrogenation of at least a portion of the propane fraction in line 41 and/or the normal butane fraction in line 39.

In most cases, however, substantially saturated butane or butane-propane fractions are preferably fed directly into line 31 leading to fractionating tower 38 by means of pump 110 and line 111 through valve 112, valve 3 of course being closed. By using this feed point excessive dilution of the reactants in alkylation chamber 7 is avoided and each of the constituent gases is readily available for use in that part of my process in which it is most needed. Any of the modifications of my process including the dehydrogenation step mentioned above can be carried out when the feed stock is charged by means of pump 110, and of course various combinations of the operating methods herein described can be used without departing from the spirit of my invention. The various steps of my process can of course be carried out on an intermittent or semi-continuous basis, and such operations are within the scope of my invention although I prefer continuous operation.

Many modifications of my invention and of the apparatus shown herein for practicing it will be apparent to those skilled in the art, who will be able to supply numerous details not illustrated in the drawing, such as heat exchangers, provisions for fractionating tower control, surge drums, etc. I do not, therefore, desire to be limited to the specific embodiments herein described, but only by the scope of the following claims.

I claim:

1. The method of producing valuable motor fuel constituents from a substantially saturated normally gaseous hydrocarbon mixture containing considerable proportions of normal butane and isobutane which comprises fractionating said mixture in a fractionating zone to form a fraction rich in normal butane and a fraction rich in isobutane, dehydrogenating a portion of said fraction rich in normal butane to form butylenes and hydrogen, introducing said butylenes and said fraction rich in isobutane into an alkylation zone containing a catalyst and maintained under conditions suitable for the reaction of butylenes and isobutane to form branched-chain octanes, removing the products from said alkylation zone, separating a normally liquid fraction containing said octanes and a normally gaseous fraction from said products, introducing said normally gaseous fraction into said fractionating zone, isomerizing the remaining portion of said fraction rich in normal butane in the presence of a catalyst of the aluminum chloride type and an activator for said catalyst at an elevated temperature to

produce a further quantity of isobutane, and utilizing said further quantity of isobutane in said alkylation zone.

2. The method of producing valuable motor fuel constituents from a substantially saturated normally gaseous hydrocarbon mixture containing considerable proportions of propane, isobutane and normal butane which comprises fractionating said mixture in a fractionating zone to form at least three fractions rich in propane, isobutane and normal butane respectively, dehydrogenating at least a portion of said fraction rich in propane to produce propylene and hydrogen, separating said propylene from said hydrogen, introducing said propylene and said fraction rich in isobutane into an alkylation zone containing a catalyst and maintained under conditions suitable for the reaction of propylene and isobutane to form branched-chain heptanes, removing the products from said alkylation zone, separating a normally liquid fraction containing said heptanes and a normally gaseous fraction from said products, introducing said normally gaseous fraction into said fractionating zone, isomerizing at least a portion of said fraction rich in normal butane in the presence of a catalyst in an isomerization zone to produce a further quantity of isobutane and utilizing said further quantity of isobutane in said alkylation zone.

3. The method of claim 2 wherein said further quantity of isobutane together with unchanged normal butane is introduced into said fractionating zone.

4. The method of claim 2 wherein a portion of said fraction rich in propane is supplied to said isomerization zone.

5. The method of producing valuable motor fuel constituents which comprises fractionating a substantially saturated normally gaseous hy-

drocarbon mixture containing considerable proportions of propane, normal butane and isobutane in a fractionating zone to form at least three fractions rich in propane, normal butane and isobutane respectively, introducing said fraction rich in isobutane into an alkylation zone for reaction with at least one olefin having three to four carbon atoms per molecule in the presence of sulfuric acid having a concentration of about 90% to 100% at a temperature of about 0° F. to about 100° F., the molecular ratio of isobutane to olefin in said alkylation zone being maintained at a value not less than about 2 to 1, passing at least a portion of said fraction rich in propane over a dehydrogenation catalyst at a temperature ranging from about 900° F. to about 1200° F. to produce propylene and hydrogen, separating said propylene from said hydrogen, introducing said propylene into said alkylation zone, passing at least a portion of said fraction rich in normal butane through an isomerization zone in the presence of a catalyst of the aluminum chloride type and an activator for said catalyst at a temperature in the range from about 250° F. to about 550° F. and a pressure of about 500 to about 6000 pounds per square inch, removing the isomerized products from said isomerization zone, introducing at least the major portion of the isobutane contained in said isomerized products into said alkylation zone, removing the products from said alkylation zone, separating a normally gaseous fraction and a normally liquid fraction containing branched-chain paraffin hydrocarbons having 7 to 8 carbon atoms per molecule from said last-mentioned products, introducing said normally gaseous fraction into said fractionation zone, and withdrawing said normally liquid fraction from the system.

RODNEY V. SHANKLAND.
